UNITED STATES PATENT OFFICE.

CHARLES L'ENFANT, OF PHILADELPHIA, PENNSYLVANIA, ASSIGNOR TO
COELESTINE L'ENFANT, OF NEW YORK, N. Y.

COVER FOR BOOKS.

SPECIFICATION forming part of Letters Patent No. 553,530, dated January 28, 1896.

Application filed April 3, 1895. Serial No. 544,264. (No model.)

To all whom it may concern:

Be it known that I, CHARLES L'ENFANT, a citizen of the United States, residing at Philadelphia, in the county of Philadelphia and 5 State of Pennsylvania, have invented certain new and useful Improvements in Covers for Books, of which the following is a specification.

This invention relates to certain improvements in the cover for books for which Letters Patent were heretofore granted to me, No. 492,925, dated March 7, 1893, whereby certain defects of said cover are overcome and a still better finish at the rounded-off 15 corners of the cover obtained.

Practical experience made with books bound with the cover heretofore patented to me show that the connection of the overlapping corner-pieces with the inwardly-bent 20 sides of the cover become frequently loose by the handling of the book and rendered the corners unsightly.

The object of this invention is to construct the rounded-off corners of the cover in such 25 a manner that a permanently-finished corner is obtained, which is not liable to get loose in any of its parts, and which presents thereby a permanently-finished and very durable corner for the covers.

30 The invention consists of a flexible cover for Bibles, prayer and other books which is made of a main body having inwardly-bent sides and of an arc-shaped narrow edge-piece extending around the rounded-off corners of 35 the main body and adapted to overlap the inwardly-bent sides, said narrow overlapping piece being worked down by creasing, so as to be permanently attached to the rounded-off corner and prevented from getting loose.

40 In the accompanying drawings, Figure 1 represents an inside elevation of my improved flexible cover for books. Fig. 2 is an inside view of the blank of one corner of the cover, drawn on a larger scale. Fig. 3 is a detail 45 view of one of the corners of the cover, showing it in partly-finished state. Fig. 4 is a like view of one of the corners, showing it in finished state; and Fig. 5 is a vertical transverse section on line 5-5, Fig. 4.

50 Similar letters of reference indicate corresponding parts.

Referring to the drawings, A represents a flexible cover for Bibles, prayer and other books, which cover is made of leather or other suitable material having the required degree 55 of flexibility. The main body of the cover A is made from a blank A', which is provided with rounded-off corners a, having at each corner a narrow strip a', that extends along the rounded-off corner of the main body, and 60 which strip is skived or pared off at its edge. The blank A is further provided with sides d, which are cut off preferably at an angle of forty-five degrees at the corners and made 65 arc shape adjacent to the main body of the blank, as at a², so that when the sides d are bent inwardly and pasted onto the main body after being skived or pared off at their under side the arc-shaped edges of the sides d coincide with the rounded-off edge of the 70 corner a of the main body, while the straight edges of the sides d abut, as shown in Fig. 3. The blank A' is cut on a sheet-metal form 75 having rounded-off corners, said blank corresponding to the size of the cover to be produced. The sides d are then bent inwardly over said frame, after which the narrow corner-pieces are also bent over and shaped carefully on the round corners of the frame. The form is then withdrawn, and the inwardly- 80 bent sides and narrow corner-pieces are pasted to the main body of the cover, so that finally the cover is formed with smooth and rounded-off corners, as shown in Figs. 1 and 4. The narrow arc-shaped corner-piece a' is 85 made to overlap the inwardly-bent sides and is carefully worked down and finally creased by means of a creasing-tool, which is specially passed over the inner skived edge of the overlapping corner-piece, as shown in Fig. 5, so 90 that the same is united to such an extent with the sides that the meeting-edges of the corner-piece cannot be perceived, whereby not only a superior finish is imparted to the corners, but also the loosening of the narrow 95 overlapping corner-pieces even by protracted handling of the book entirely obviated.

A interior lining e, of thin smooth leather, is pasted over the inside of the cover and creased at the edge in similar manner to the 100 creasing of the outer edges of the cover, so that a flexible cover with rounded-off cor-

ners is thus obtained that extends over the body of the book and forms a neat, strong and durable cover for the same.

Having thus described my invention, I claim as new and desire to secure by Letters Patent—

1. A flexible cover for Bibles and other books, composed of a main - body having rounded-off corners, inwardly-extending side-pieces bent from the main-body and formed with curved edges, merging directly from the straight side edges of the main-body and conforming to the curvature of and matching with the rounded - off corners of the main-body, said side-pieces being also formed with straight ends, arranged at an angle of forty-five degrees to the longitudinal edges thereof, and joined so as to extend radially inward from the corners of the main-body, and narrow arc-shaped corner-pieces extending inwardly from the rounded-off corners of the main-body and overlapping the curved parts of the inwardly - bent side - pieces, the side-

edges of the corner-pieces extending from the straight side-edges of the main-body substantially as set forth. 25

2. A blank for flexible covers of books, provided with narrow arc - shaped corner-pieces in recesses formed in its corners, and side-pieces provided with straight outer ends 30 each at an angle of forty-five degrees to the longitudinal edge of the side, and with inwardly - curved edges extending from said straight outer ends to the folding line of the said pieces, the portions of the side-pieces 35 bounded by said straight outer edges and the curved edges extending beyond the corner-pieces, substantially as set forth.

In testimony that I claim the foregoing as my invention I have signed my name in presence of two subscribing witnesses. 40

CHARLES L'ENFANT.
